UNITED STATES PATENT OFFICE.

RALPH P. MERCER, OF BURLINGTON, IOWA.

AUTOMATIC DRAFT-REGULATOR.

1,114,788.

Specification of Letters Patent.

Patented Oct. 27, 1914.

Application filed March 14, 1914. Serial No. 824,698.

To all whom it may concern:

Be it known that I, RALPH PAUL MERCER, a citizen of the United States, residing at Burlington, in the county of Des Moines and State of Iowa, have invented certain new and useful Improvements in Automatic Draft-Regulators, of which the following is a specification, reference being had to the accompanying drawings.

10 This invention relates to certain improvements in automatic draft regulators and has relation more particularly to a device of this general character especially designed and adapted for use in connection with furnaces; and an object of the invention is to provide a device of this general character having novel and improved means whereby the draft is under control of a mechanism driven by an electric motor.

20 The invention also has for its object to provide a device of this general character having novel and improved means whereby the operating circuit for the motor is under control of a thermostatic switch.

25 The invention consists in the details of construction and in the combination and arrangement of the several parts of my improved automatic draft regulator whereby certain important advantages are attained and the device is rendered simpler, less expensive and otherwise more convenient and advantageous for use, all as will be herein-after more fully set forth.

The novel features of the invention will 35 be carefully defined in the appended claim.

In order that my invention may be the better understood, I will now proceed to describe the same with reference to the accompanying drawings, wherein—

40 Figure 1 is a diagrammatic view illustrating a draft regulator constructed in accordance with an embodiment of my invention; Fig. 2 is a view in side elevation of the operating mechanism as herein disclosed; Fig. 45 3 is a view in top plan of the device as illustrated in Fig. 2; Fig. 4 is a fragmentary view in top plan, on an enlarged scale, illustrating one of the circuit closers herein embodied, such closer being shown in open relation; Fig. 5 is a view similar to Fig. 4 but illustrating the closer in closed relation; Fig. 6 is a fragmentary view in elevation of the brake mechanism herein included; and Fig. 7 is a view, detached, of the pin included in the brake mechanism.

As disclosed in the accompanying draw-

ings, 1 denotes a furnace of any ordinary or preferred construction provided with the dampers 2 of conventional form having operatively connected thereto the flexible members 3 disposed around suitable guide pulleys or rollers 4 and branching from a main flexible member 5 operatively connected with a crank 6 produced on a shaft 7, to be hereinafter more particularly referred to. 60 The relation of the parts, hereinbefore referred to, is such that when the crank 6 is in an upstanding vertical position the dampers 2 will be in one adjustment and when the crank 6 is in an opposite position the dampers 2 will be reversely related, for purposes which are believed to be self-evident.

65 As herein disclosed, the shaft 7 is rotatably supported in the bearings 8 carried by the base plate 9 and has affixed thereto a 70 toothed wheel 10 of predetermined dimensions, which wheel is in mesh with a toothed pinion 11 affixed to the driven shaft 12 mounted in suitable bearings 14 supported upon the base 9. The shaft 12 has also 75 suitably affixed thereto the grooved pulley 15 around which is disposed the driving belt 16 also directed around the grooved pulley 17 affixed to a driving shaft 18 of the motor 19, such motor being herein disclosed 80 as of an electrical type.

85 Positioned at any predetermined locality is the thermostatic switch 20 including the thermostatic bar 21 which plays between the contacts 22 so as to close a circuit, as will 90 hereinafter be more fully set forth, according as the temperature rises or lowers in the locality in which such switch 20 is arranged.

95 23 indicates a source of electrical energy connected with the motor 19 by the wire *a* and in connection with the thermostatic switch 20 by the wire *b*, while the contacts 22 are in connection with the circuit closers 24, which will hereinafter be described, by the wires *c* and *d*, which circuit closers 24 are in connection with the motor 19 through the medium of the bar 25 and the wire *e*.

100 The circuit closers 24 are under control of the wheel 10 so that when the motor has been caused to move the crank 6 to a requisite extent, the operating circuit of the motor is broken. As shown in the accompanying drawings, I suitably position adjacent the wheel 10 the upstanding bar or support 25, herein disclosed as of conductive material and maintained in operative position by the 110 upstanding bracket 26 suitably connected

with the base 9. Produced on the adjacent face of the wheel 10 and in close proximity to the periphery thereof is the arcuate flange or shoulder 27 slightly in excess of a semi-circle, which shoulder or flange 27 is adapted to force the spring contact members 28 and 29 of each of the closer members 24 into contact one with the other so that the requisite circuit will be completed in accordance with 5 the position of the thermostatic bar 21. As herein disclosed, the spring contact members 28 are secured directly upon the bar or support 25 and are of a length in excess of the length of the contacts 29 which are also operatively supported by the bar or member 25 but properly insulated, as is indicated at 30, from the contact 28, as is clearly shown in the drawings, and it is to the outer contacts 29 that the wires *c* and *d* are operatively 10 connected.

As disclosed in Fig. 1, the circuit to the motor 19, with the upper closer 24 in closed adjustment, would be through the wires *a*, *b* and *d*, the supporting member or bar 25 15 and wire *e*, but, as shown in Fig. 2, it will be observed that the wheel 10 has been sufficiently rotated by the motor 19 as to bring the crank 6 into a desired position and in which instance, the lower or inner spring contact 28 20 of the upper closer 24 has been freed from the flange or shoulder 27 and thus broken the circuit. It will also be observed from the diagrammatic disclosure in Fig. 1 that with the upper circuit closer 24 in open position, the shoulder or flange 27 is of such an extent as to have adjusted the spring contacts of the lower closer 24 into operative engagement so that immediately upon the thermostatic bar 21 engaging the opposite 25 contact 22, the motor 19 will immediately respond, in which instance the circuit will be through the wires *a*, *b* and *c*, the supporting member or bar 25 and the wire *e*.

With the stopping of the motor 19, the 30 heavier damper 2 would have a tendency to impart a retrograde movement to the wheel 10, as is believed to be self-evident, but, in order to avoid this disadvantage, I provide the brake pin 31 slidably engaged within the 35 vertically disposed elongated slot 32 produced in the upper extremity of a bracket 33, herein disclosed as operatively connected with a bearing 14 and which is adapted to engage by gravity the teeth of the wheel 10 40 and thus effectively maintain such wheel against rotation in a direction opposite to the rotation thereof under the influence of the motor 19, it being readily perceived that the elongated slot 32 permits the pin 31 to 45 be disengaged from such wheel 10 upon its proper rotation. While I do not wish to be

particularly limited as to the exact form of the pin 31, I find it of advantage to have one extremity provided with the annular groove or channel 34 adapted to receive the longitudinal marginal portions of the elongated slot 32.

From the foregoing description, it is thought to be obvious that an automatic draft regulator constructed in accordance with my invention is of an extremely simple and comparatively inexpensive nature and is particularly well adapted for use by reason of the convenience and facility with which it may be assembled and by reason of the effectiveness with which it performs its several functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with a movable member, a device comprising a motor, a source of electrical energy, connections between such source and the motor, a thermostatic closer interposed in the connections, a mechanical closer interposed therein including a shaft, a flexible connection between the shaft and movable element whereby the same may be automatically adjusted, a gear wheel mounted on the shaft, a second shaft provided with a gear in mesh with the first mentioned gear, an operative connection between the second named shaft and the motor, a slotted bracket positioned adjacent the point of engagement between the first named gears, a pin having one extremity slidably engaged within the slot of the bracket and adapted to engage the teeth of the first named gear for holding said wheel against rotation in one direction, an arcuate flange carried by a side of the first named gear in excess of a semi-circle, a supporting bar positioned adjacent one side of the wheel and in spaced relation thereto, circuit closers carried by the bar and diametrically opposed relative to the wheel, each of said closers comprising a pair of normally spaced spring contacts, one of said contacts being of a length in excess of the second contact and adapted to be engaged by the flange of the gear.

In testimony whereof I hereunto affix my signature in the presence of two witnesses.

RALPH P. MERCER.
